Specification for Design.

Patented Nov. 24, 1914.

Application filed September 9, 1913. Serial No. 788,976. Term of patent 14 years.

To all whom it may concern:

Be it known that I, Guss A. Swanson, a citizen of the United States, residing at Seattle, in the county of King and State of Washington, have invented a new, original, and ornamental Design for Building-Blocks, of which the following is a specification, reference being had to the accompanying drawing, forming part thereof.

In the drawings, Figure 1 is a perspective view of a building block showing my new

design. Fig. 2 is an end elevation of the same. Fig. 3 is a side elevation taken in the direction indicated by arrow 3 in Figs. 1 and 2.

I claim:

The ornamental design for a building block, as shown.

GUSS A. SWANSON.
